(57) **CLAIM**

The ornamental design for a module for construction of a rotary disc filter, as shown and described.

DESCRIPTION

FIG. 1 is a perspective view showing the top side, the right side and the front of the module for construction of a rotary disc filter according to the new design; and

FIG. 2 shows the module from the front;

FIG. 3 shows the module from the back;

FIG. 4 shows the module from the right;

FIG. 5 shows the module from the left;

FIG. 6 shows the module from above; and,

FIG. 7 shows the module from below.
